FREEZING TRAY

Ralph H. Chilton, Dayton, Ohio, assignor to General Motors Corporation, Detroit, Mich., a corporation of Delaware

Application December 27, 1937, Serial No. 181,940

15 Claims. (Cl. 62—108.5)

This invention relates to freezing trays, especially such as are adapted for use in household refrigerators.

An object of this invention is to provide an improved form of portable ice tray from which the ice blocks may be readily removed without the necessity of thawing them loose.

Many devices have heretofore been devised for the same purpose, hence the various important 10 novel features of this device are pointed out as follows:

1. Simplicity of design and economy of manufacture. The resilient rubber cross partitions do not have to be separately molded but may, if desired, be cut out from a large rubber sheet thus greatly reducing their cost. The upper and lower metal plates forming the longitudinal division wall may be easily assembled to the cross partitions simply by stretching the size of the 20 slots in the resilient rubber cross partitions until they are snapped into proper place. The resilient cross partitions then resiliently retain the metal plates in their normal position but permit easy relative movement therebetween.

2. Simplicity and strength of the ejecting mechanism. The hand lever has all necessary operating cams unitary therewith and thus avoids 25 separate actuating links, bars, cams, etc. The shape of the cams on the hand lever may be readily chosen to give any desired mechanical advantage either to force the container pan from its contents or to force a separation of the two metal plates forming the central division wall. Since the separating movement necessary to

35 loosen one of the central metal plates from its bond to the ice is very small, the mechanical advantage of the corresponding cams may be very large and still provide a very simple strong and rugged cam structure. The twisting distortion of the resilient upper metal plate by means 40 of the hand lever is of utmost simplicity and is progressive from end to end thereof thus greatly facilitating the loosening of the ice blocks from the grid.

45 3. Ease of operation. Due to successive loosening operations of the various parts from their bond to the ice the force required to remove the ice blocks is relatively small. Also the grid structure is simplified and rendered more efficient by 50 providing that the ice block compartments be only partially formed by the division walls which leave interconnecting necks of ice of substantial sectional area. These interconnecting necks of ice are readily successively cracked in two by the 55 operation of the device since there are no edges

or shoulders on the grid parts to positively resist the relative movement of the ice blocks necessary to crack them in two.

Further objects and advantages of the present invention will be apparent from the following description, reference being had to the accompanying drawings wherein a preferred embodiment of the present invention is clearly shown.

In the drawings:

Fig. 1 is a plan view of an ice tray made according to this invention.

Fig. 2 is a section taken on line 2—2 of Fig. 1.

Fig. 3 is a section on line 3—3 of Fig. 2 of the grid removed from the pan.

Fig. 4 is a section on line 4—4 of Fig. 2 of the grid removed from the pan.

Fig. 5 is a view illustrating the operation of the grid to loosen the ice cubes after the pan has been removed. Fig. 5 is taken along line 4—4 of Fig. 2.

Fig. 6 is a plan view illustrating the successive loosening of the ice cubes from the grid by the lateral twisting of the upper metal plate by the hand lever.

Similar references relate to similar parts throughout the several views.

The container pan 10 may be of any suitable design or material, but is preferably a drawn sheet aluminum pan having outwardly inclined 30 side and end walls and having such a degree of resiliency that it may be slightly distorted by the hand lever to facilitate its loosening from its frozen contents.

The removable grid illustrated in the drawings 35 comprises a metal longitudinal division wall 15 and a plurality of flexible rubber transverse walls 30 mounted thereupon. Wall 15 comprises an upper resilient metal plate 16 and a lower metal plate 17 which are mutually relatively movable. 40 A hand lever 18 is pivoted upon the upper plate 16 by pivot pin 19 adjacent one end thereof. Lever 18 preferably has a U-shaped section adjacent pin 19, thus providing two strong depending side flanges 20 which snugly contact the plate 45 16 and provide an efficient means for twisting plate 16 laterally as described hereinafter.

The lower edges of side flanges 20 form cams 21 which engage cam surfaces 22 on the lower plate 17 during the ejecting operation and thus 50 efficiently provide a great force to separate the two plates 16 and 17 in a vertical direction. Preferably the cam surfaces 22 are formed by separate metal plates 23 rigidly fixed to opposite sides of the metal plate 17 by suitable riveting 55

or spot welding in order to form the very strong lateral surfaces 22 which obviously should have a greater lateral width than the upper plate 16. When the parts are in freezing position, as shown 5 in Fig. 2, there is preferably a small clearance 24 between cams 21 and cam surfaces 22 in order to permit a slight rotation of lever 18 before these surfaces engage each other.

The forward edges of the two side flanges 20 10 form a cam 25 which is so shaped as to force the lip 11 of pan 10 outwardly and downwardly and thereby loosen the ice bond between pan 10 and its frozen contents prior to high pressure being exerted between cams 21 and cam surfaces 22, 15 upon rotation of hand lever 18 in the direction of arrow A in Fig. 2. If desired, the lateral width of cam 25 may be increased for providing a greater bearing area upon the pan lip 11.

With the form of the invention shown in Fig. 2, 20 when the hand lever 18 is swung upwardly the cam 25 first engages the pan lip 11 and forces the pan 10 loose from its frozen contents by a progressive peeling action of the pan from its ice contents. During this operation the upper plate 25 16 is held against relative movement with plate 17 due to being partially embedded and frozen solid in the ice. However when the cams 21 exert pressure upon the surfaces 22, the upper plate 16 is normally tilted upwardly with a very great 30 force to loosen the ice bond between the embedded portion of plate 16 and the frozen contents. It will be noted that the shape of cam 21 may be chosen independently of the shape of cam 25 so as to permit the best and most efficient 35 cam shape for each of these operations. Preferably cam 21 is so shaped as to provide only a very slight upward tilting of plate 16 in order to provide a very large mechanical advantage for this initial loosening of plate 16 from its ice bond. 40 But after plate 16 is so loosened from its ice bond and hand lever is further rotated to a substantially vertical position, the cam 25 will also engage cam surfaces 22 and easily give a further upward tilting of plate 16 so as to lift plate 16 45 from its groove in the ice to the desired extent before giving plate 16 its lateral twisting distortion (see Fig. 5). It will be noted that the strong lateral flanges 20 on lever 18 will still snugly engage the opposite sides of plate 16 when lever 18 50 is in its substantial vertical position and thus provide a very strong and efficient grip thereupon for distorting plate 16 laterally by moving lever 18 to and fro in a lateral direction as illustrated in Fig. 5. Plate 16 may be made of re- 55 silient stainless steel or other springy metal capable of considerable torsional distortion without permanent set. The lower plate 17 may be made of any suitable metal but preferably of anodized aluminum having a wax treated surface in order 60 to more readily loosen from the ice.

The cross walls 30 and 31 are preferably made of flexible rubber but obviously may be of any suitable distortable material which will permit the above-described relative movements between 65 upper plate 16 and lower plate 17. These flexible rubber walls may be very cheaply made by cutting same from a large flat sheet rather than by molding the individual walls. Walls 30 are each provided with a central slot 32 thru which the 70 metal plates 16 and 17 may be readily forced for assembling the various parts together. After such assembling the walls 30 snugly fit into the upper notches 33 in plate 16 and lower notches 34 in plate 17 and thus all these parts are yield- 75 ably retained in their normal freezing position

shown in Figs. 1, 2, and 3. The necks of rubber 35 overlying plate 16 are somewhat stretched when plate 16 is tilted upwardly as above described. Preferably notches 33 in plate 16 progressively decrease in depth toward the end 5 thereof to which lever 18 is pivoted in order that plate 16 will be more resistant to torsional distortion at the lever end thereof and progressively decrease in torsional resistance to the other end thereof. In Fig. 2 the first rubber cross wall 10 31 is shown as having no neck of rubber overlying plate 16 and hence no notch 33 in the upper edge of plate 16 at this point. This is for the purpose of avoiding any weakening of the torsional resistance of plate 16 by a notch in the 15 metal thereof so close to the pivot pin 19. Hence this first cross wall 31 is properly retained in place by a neck of rubber 36 which extends thru a corresponding notch in the upper edge of plate 17 (see Fig. 2). The two upstanding portions 37 20 of cross wall 31 preferably contact plate 16 but are not attached to plate 16 and hence do not oppose upward tilting of plate 16 at this point.

Obviously all the flexible rubber cross walls will 25 be easily distortable to permit the twisting distortion of plate 16 by hand lever 18 as above described and as illustrated in Fig. 6. When lever 18 is swung laterally after it reaches a substantial vertical position, the lower portion of plate 16 which still lies within its groove in the ice is 30 forced laterally against the ice blocks on each side thereof and causes them to split off the lower metal plate 17 and in so doing to crack in two at 41 across the interconnecting necks of ice 40 of substantial cross sectional area (see Fig. 5). 35 Of course if desired, the metal plate 17 can extend all the way to the bottom of the ice blocks and thus provide somewhat more rapid freezing due to the better heat conduction of the greater area of metal partitions in the grid. However it 40 has been found in certain cases that it is easier to crack the ice in two over a substantial area rather than to force it loose from the two opposite sides of a metal partition wall. For instance, in the above device, it is easier to crack the ice 45 in two over the substantial areas 41 than it would be to force them free from opposite sides of a metal partition wall extending across these areas 41. In fact the metal plate 17 may have a 50 materially less depth than that illustrated in the drawings and still the substantially larger interconnecting necks of ice 40 would be cracked in two by the above-described operation of the device. The vertical depth of the bottom plate 17 may be only such as will give the desired 55 strength and rigidity for properly carrying the reaction of cams 21 and 25 thereupon. After the ice blocks are loosened from the metal plates 16 and 17 by actuation of lever 18 they will either fall out or may be easily picked from the resilient 60 rubber cross walls. Note that the above described operation stretches and otherwise distorts these rubber cross walls, which of course aids in freeing the ice from these cross walls.

It will be clear to those skilled in the art that 65 the very simple and efficient means of this invention for moving two sections of a main division wall relative to one another is not limited to a grid structure having flexible non-metallic cross walls. Various embodiments may be readily designed wherein the cross walls are of metal and loosely mounted upon the main division wall in such a way as to permit relative vertical movement between the upper and lower sections of 70 said main division wall in order to force a pro- 75

gressive loosening of the ice from the division walls.

While the embodiment of the present invention as herein disclosed, constitutes a preferred form, it is to be understood that other forms 5 might be adopted, all coming within the scope of the claims which follow.

What is claimed is as follows:

1. In a freezing tray, a container pan, a grid 10 for dividing the pan into a plurality of ice block compartments, said grid comprising: a longitudinal wall having substantially aligned relatively movable upper and lower sections, a plurality of transverse walls mounted upon said longitudinal wall so as to permit substantial relative lateral motion and relative vertical motion 15 between said upper and lower sections, and force-multiplying means for moving said upper section substantially in a vertical plane and thereby loosening it from the ice and for thereafter moving said upper section laterally to force the ice upon opposite sides thereof loose from said lower section.

2. In a freezing tray, a container pan, a grid 20 for dividing the pan into a plurality of ice block compartments, said grid comprising: a longitudinal wall having substantially aligned relatively movable upper and lower sections, a plurality of transverse walls mounted upon said longitudinal wall and permitting a substantial relative lateral motion and relative vertical motion 25 between said upper and lower sections, and force-multiplying means for tilting one end of said upper section upwardly relative to said lower section and for distorting said upper section to force the ice blocks laterally from said longitudinal wall.

3. In a freezing tray, a container pan, a grid 30 for dividing the pan into a plurality of ice block compartments, said grid comprising: a longitudinal wall having substantially aligned relatively movable upper and lower sections, a plurality of transverse walls mounted upon said longitudinal wall and permitting a substantial relative lateral motion and relative vertical motion 35 between said upper and lower sections, and force-multiplying means arranged to first force a separating movement between said upper and lower sections and thereby loosening at least one of 40 said sections from the ice, and adapted to longitudinally twist said upper section to force the ice blocks laterally from said longitudinal wall.

4. In a freezing tray, a container pan, a grid 45 for dividing the pan into a plurality of ice block compartments, said grid comprising: a main longitudinal wall having relatively movable metallic upper and lower sections both normally bonded to the frozen ice contents, a plurality of resilient non-metallic transverse walls mounted upon said longitudinal wall and permitting relative movement 50 between said upper and lower sections, and force-multiplying means arranged to force a relative movement between said sections and thereby loosen at least one of said sections from its frozen bond to the ice, and to distort said upper section to force the ice blocks laterally from said longitudinal wall.

5. In a freezing tray, a container pan, a grid 55 for dividing the pan into a plurality of ice block compartments, said grid comprising: a main longitudinal wall having relatively movable metallic upper and lower sections both normally bonded to the frozen ice contents, a plurality of resilient non-metallic transverse walls mounted upon said 60 longitudinal wall and permitting relative move-

ment between said upper and lower sections, and force-multiplying means arranged to force a relative tilting movement between said sections and thereby loosen at least one of said sections from its ice bond, and to distort said upper section to force the ice blocks laterally from said longitudinal wall. 5

6. In a freezing tray, a container pan, a grid 10 for dividing the pan into a plurality of ice block compartments, said grid comprising: a main longitudinal wall having relatively movable metallic upper and lower sections both normally bonded to the frozen ice contents, a plurality of resilient non-metallic transverse walls mounted upon said longitudinal wall and permitting relative movement 15 between said upper and lower sections, and force-multiplying means arranged to force a relative movement between sections and thereby loosen at least one of said sections from its frozen bond to the ice, and to move said upper section 20 in such manner as to force the ice blocks laterally from said longitudinal wall.

7. In a freezing tray, a container pan, a grid 25 for dividing the pan into a plurality of ice block compartments, said grid comprising: a main division wall having relatively movable metallic sections both normally bonded to the frozen ice contents, a plurality of resilient non-metallic cross walls permitting relative movement 30 between said metallic sections, and force-multiplying means arranged to force a relative movement between said metallic sections and thereby loosen at least one of said sections from its frozen bond to the ice, and to move one of said sections in such manner as to force the ice blocks laterally 35 from said main division wall.

8. A unitary dividing grid for a freezing tray, comprising: a main division wall having at least 40 partially relatively separatable upper and lower sections both normally bonded to the frozen contents, and a force-multiplying hand lever pivotally mounted upon said upper section and arranged to force a partial relative separating movement 45 between said sections and thereby at least partially loosen one of said sections from its frozen bond to the ice contents, and to then move one of said sections laterally to engage and force the ice contents laterally from said main division wall. 50

9. A unitary dividing grid for a freezing tray, comprising: a main division wall having at least 55 partially relatively separatable upper and lower sections both normally bonded to the frozen contents, and a force-multiplying hand lever pivoted upon said upper section and arranged to force a relative separating movement between said sections and thereby at least partially loosen one of said sections from its frozen bond to the ice contents, and to then give a twisting distortion to one of said sections to force the ice contents laterally from said main division wall. 60

10. A unitary dividing grid for a freezing tray, comprising: a main division wall having at least 65 partially relatively separatable upper and lower sections both normally bonded to the frozen contents, and a force-multiplying hand lever pivoted upon said upper section and arranged to tilt one end of said upper section upwardly and thereby at least partially loosen said upper section from its frozen bond to the ice contents and to distort said upper section to force the ice contents laterally from said main division wall. 70

11. A unitary dividing grid for a freezing tray, comprising: a main division wall having relatively separatable upper and lower sections both 75

- normally bonded to the frozen contents, and an actuating lever pivotally mounted upon said upper section and reacting upon said lower section and operable to force a relative separating movement between said sections whereby one of said sections is at least partially loosened from its frozen bond to the ice contents, said lever being operable to distort said upper section laterally to force the ice contents laterally from said main division wall.
12. A dividing grid for a freezing tray, comprising: a main division wall having relatively separatable upper and lower sections both normally bonded to the frozen contents, a plurality of resilient non-metallic cross walls permitting relative movement between said upper and lower sections, and an actuating lever mounted upon said upper section and reacting upon said lower section and operable to force a relative separating movement between said sections to at least partially loosen one of said sections from its frozen bond to the ice, said lever being also operable to distort said upper section to force the ice contents laterally from said main division wall.
13. A dividing grid for a freezing tray, comprising: a resilient metal plate constituting at least an ice-contacting portion of a main division wall of said grid, a plurality of resilient rubber cross walls extending laterally of said main wall to form walls of ice block compartments, said
- rubber walls permitting a twisting distortion of said resilient metal plate, and means for giving said resilient plate a progressive twisting distortion to loosen the ice blocks therefrom.
14. A dividing grid for a freezing tray, comprising a resilient metal plate constituting at least an ice-contacting portion of a main division wall of said grid, a plurality of resilient rubber cross walls extending laterally of said main wall to form walls of ice block compartments, said rubber walls permitting a twisting distortion of said resilient metal plate, and a hand lever mounted upon one end of said resilient metal plate and operable to progressively twist said plate to loosen the ice blocks therefrom.
15. In a freezing tray, a container pan, a grid for dividing the pan into a plurality of ice block compartments, said grid comprising: a resilient metal plate constituting at least a substantial portion of a main division wall of said grid, a plurality of resilient rubber cross walls extending laterally of said main wall to form walls of ice block compartments, said rubber walls permitting a relative twisting distortion of said resilient plate, and a hand lever mounted upon said metal plate and operable to initially react upon said pan to loosen the frozen bond between said pan and its contents, said lever being also operable to progressively twist said plate to loosen the ice blocks therefrom.

RALPH H. CHILTON.
